UNITED STATES PATENT OFFICE.

ROBERT E. ADAMS, OF NEW YORK, N. Y., ASSIGNOR TO ADJUSTABLE GUN CASE CORPORATION, OF NEW YORK, N. Y., A CORPORATION OF NEW YORK.

GUN CASE.

Application filed May 25, 1926. Serial No. 111,543.

This invention relates to cases or containers for shot guns and the like.

Gun cases, as heretofore usually constructed, have been designed to fit one or more particular styles or types of gun. This compelled manufacturers to make a large number of different patterns, and necessitated dealers carrying a large assortment, thus increasing the cost of making and handling these articles.

The primary object of the present invention is to devise a standard type of gun case which shall be capable of containing any style or type of shot gun now on the market, that is to say, a universal case. By thus enabling manufacturers to concentrate their activities upon a single standard pattern or style of case, the manufacturing cost is proportionately reduced. Likewise, dealers will have to carry only one kind of case, and therefore, smaller stocks will be sufficient. Thus, the cost of handling will be reduced.

A further object of the invention is to provide a relatively cheap and serviceable substantially rigid combined gun and cartridge case, which shall be substantially waterproof and capable of withstanding rough usage.

With the above and other objects in view, the invention consists in the construction and combination of parts hereinafter described and claimed, and illustrated in the accompanying drawings, in which:

Figure 1 is a perspective view of my improved gun case in its open position, showing it as it appears when adjusted to receive one type of gun;

Figure 2 is a plan view thereof, showing the parts adjusted to receive a different type of gun;

Figure 3 is an enlarged fragmentary sectional plan view, through the partition adjusting means shown at the left hand end of the case; and

Figure 4 is a fragmentary plan view on an enlarged scale, showing one of my improved extensible partitions, parts being in section.

Referring to the drawings in detail, my improved case comprises a box-like container 1, formed of some relatively stiff and inexpensive material, such, for example, as indurated fiber board. The container is reinforced at its edges by a double thickness of material, as indicated at 2, and is provid-

ed with a top 3, hinged at 4, after the manner of an ordinary trunk or suitcase. Fasteners 5 and a lock 6—7 of the usual or any desired construction are preferably provided, and the case is equipped, adjacent the lock, with a handle 8, by means of which it may be conveniently carried.

In order to divide the container into compartments capable of snugly receiving the different parts of a gun, I provide a pair of rigid longitudinal partitions 9 and 10. One of these partitions 9 has a notch 11 formed therein, as clearly shown in Figure 1, this notch being for the purpose of receiving the projection which is usually found on the barrel portion of shot guns of the automatic type. The other partition 10 is solid and of uniform width throughout.

At each end of each longitudinal partition is provided a projecting tongue or the like 12, and these tongues are adapted to be received in sockets or slots at the respective ends of the container. These slots are preferably formed in wooden end pieces 13 and 14, secured inside the case, as shown in the drawings.

At one end, as shown at the right hand portion of Figures 1 and 2, the flat strip or end piece 14 is employed in which one or more vertical slots or sockets 16 are formed.

At the other end of the container I have shown the end piece 13 as consisting of a relatively thick wooden strip in which sockets or slots 15 are cut. These slots receive the tongue 12 at the end of the partition, the same as the slots 16 at the other end of the container.

By reference to Figures 2 and 3, it will be particularly noted that the inner surface of the end piece 13, adjacent the slots or notches 15, is cut on an arc substantially around one of the notches 16 as a center. Moreover, the notches 15 are not parallel, but are radial to this arc.

It will now be apparent that the two longitudinal partitions 9 and 10, which differ from one another in that the partition 9 is provided with the notch 11, while the partition 10 is unbroken, are of the same length and size, and are therefore interchangeable. That is to say, in Figure 1, the partition 9 is shown with its ends engaged in the sockets or slots 15 and 16, while the partition 10 is illustrated as lying snugly against the inside of the front wall of the container, spe-

cial sockets 15^a and 16^a being provided in the end pieces 13 and 14 for this purpose. In Figure 2, the partitions are reversed, partition 10 being in engagement with the sockets 15 and 16, while partition 9 lies against the wall of the container.

From an inspection of the drawing, it will also be apparent that the projections 12 at the ends of either one of these partitions may 10 be inserted in any of the slots 15 or 16, and that by this means, the position of such partition relative to the side walls of the container, may be varied. Furthermore, it will be seen that the right hand end of the partition 15 may remain engaged with one of the slots or sockets in the end piece 14, while the left hand end may be swung about such slot as a pivot, and engaged in any one of the slots 15. In this way, the angular relation 20 of the partition to the side walls of the container may be varied.

In addition to the longitudinal partitions 9 and 10, I provide transverse partitions 17 and 18, which extend between the longitudinal partitions. In order to permit of the adjustment of the longitudinal partitions in the sockets 15 and 16, as described, it is necessary to make the transverse partitions telescopic or extensible. To this end, each of 25 these transverse partitions is mounted at each end in a sleeve or cuff 19, into and out of which it may slide, as required, these sleeves being provided with outturned edges 20, which are adapted to engage in grooves 30 formed by the bent over edges of suitable clips 21, preferably formed of sheet metal, and secured to the partitions 9 and 10 by means of screws 22 (see Figure 4).

From the foregoing, it will be seen that 40 the partitions divide the container into a number of compartments. Compartment A is designed to receive the stock portion of the gun, while compartment B receives the barrel portion. Compartments C and D, at 45 each end of the compartment A, are designed to contain shells, or other accessories, such as cleaning implements.

The object of providing two partitions 9 and 10, and making them interchangeable, 50 is as follows. As above stated, the notch 11 is for the purpose of receiving a partition of the mechanism attached to an automatic gun barrel. This is, of course, a single barrel gun, and relatively light. The cutting 55 away of the partition 9 to form the notch 11 necessarily weakens it, and if this weakened partition were used to hold a heavy piece such as a double barrel or repeating gun, it might not be strong enough. Therefore, 60 when adapting the case to hold a double barrel or similar heavy gun, other than an automatic, I place the partition 9 against the wall of the container, as shown in Figure 2, and use the uniform stronger partition 10 65 in its place.

In the drawing, the partitions 17 and 18 are shown in arbitrarily selected positions by way of example. It will, of course, be understood that they can be placed in any desired position. It will be noted, however, 70 that in Figures 1 and 2, the relative location of these partitions is reversed, because of the fact that the longitudinal partitions 9 and 10 are shown reversed in the two figures.

In practice, I propose that the gun case, 75 as furnished to dealers, will not have the clips 21 fastened in position, but these clips, and the partitions 17 and 18, will be packed in the container, with the necessary screws. A purchaser may then easily secure the clips 80 to the partitions 9 and 10 in any position best adapted for the requirements of the particular gun for which the case is wanted. In other words, he can place the clips in such a position that the compartment A, when the 85 partitions are assembled, will be of just the proper length to snugly receive the stock portion of his gun. Having done this, he can set the partition 9 or 10 in the slots or sockets 15 and 16 in such a position as will 90 make the compartment B just wide enough to snugly hold the barrel portion of his gun.

It will thus be seen that by the above described arrangement of partitions, I have provided a gun case of simple construction 95 which is of universal adaptability and which may be readily adjusted to properly hold any one of the various well known types of guns.

What I claim is:—

1. A gun case comprising a box like container, of greater length than width, said case having a rigid partition extending lengthwise thereof, and provided with means whereby said partition may be secured in 105 any one of several positions at different angles to the sides of the container.

2. A gun case comprising a box like container, of greater length than width, said case having a rigid partition extending 110 lengthwise thereof, and provided at its ends with locking projections, each end of the container being formed with a plurality of sockets to receive said projections, said 115 sockets being so positioned that said locking projections may be inserted simultaneously into any two sockets at opposite ends of the container, whereby the angle of the partition relative to the sides of the container may be varied.

3. A gun case comprising a box like container, of greater length than width, said case having a rigid partition extending lengthwise thereof, and provided at its ends with locking projections, each end of the 125 container being provided with a group of spaced sockets to receive said projections, one of said groups of sockets being located adjacent one side wall of the container, and the other group being further from said side 130

wall, whereby said partition may be secured in any one of a plurality of positions, in all of which it extends at an angle to the side walls of the container.

- 5 4. A gun case comprising a box-like container, of greater length than width, said case having a rigid partition extending lengthwise thereof, and provided at its ends with locking projections, a socket at one
10 end of the container to receive one of said projections, and a member at the other end of the container having a plurality of sockets into any one of which the other of said projections may be inserted, the inner face of
15 said member adjacent said sockets being formed on an arc substantially around said first mentioned socket as a center.
5. A gun case comprising a box like container, of greater length than width, said
20 case having a rigid partition extending lengthwise thereof, means for securing said partition in different positions relative to the sides of the container, and a transverse

extensible partition detachably secured to said longitudinal partition. 25

6. A substantially rigid gun case of elongated form having longitudinal and transverse partitions dividing the same into a plurality of compartments, said transverse partitions being extensible, and means for 30 securing the longitudinal partition in different positions, whereby the relative sizes of said compartments may be varied.

7. The combination with a gun case comprising a substantially rigid, elongated container, of a pair of interchangeable longitudinal partitions mounted therein, said partitions being of different structural shape but the same length, means for securing said partitions in the container with one parallel 35 to the side walls thereof and the other at an angle thereto, and a transverse partition extending between them.

In testimony whereof I affix my signature.

ROBERT E. ADAMS.
